DESIGN FOR A CLAMP

John Oros and Gordon R. Dawson,
Cleveland, Ohio

Application November 28, 1947, Serial No. 142,848

Term of patent 14 years

(Cl. D54—13)

To all whom it may concern:

Be it known that we, John Oros and Gordon R. Dawson, citizens of the United States, residing at Cleveland, in the county of Cuyahoga and State of Ohio, have invented a new, original, and ornamental Design for Clamp, of which the following is a specification, reference being had to the accompanying drawing, forming part hereof, wherein:

Figure 1 is a view in side elevation of the clamp showing our new design;

Figure 2 is a view in side elevation of the reverse side of that shown in Figure 1; and

Figure 3 is a view in top plan of the clamp.

We claim:

The ornamental design for a clamp, substantially as shown.

JOHN OROS.
GORDON R. DAWSON.
